Primary Examiner — Darlington Ly*Assistant Examiner* — Giang Hoang Tran(74) *Attorney, Agent, or Firm* — Tucker Ellis LLP(57) **CLAIM**

The ornamental design for a bumper end cap, as shown and described.

DESCRIPTION

FIG. 1 is a top, front and right side perspective view of a bumper end cap showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

A second embodiment of the claimed design for the bumper end cap is a mirror image of the bumper end cap as shown in FIGS. 1 to 7.

1 Claim, 4 Drawing Sheets(56)
